CIRCUIT CLOSER FOR FLASHLIGHTS

Orville T. Wood, Clinton, Mass., assignor to Blake Manufacturing Corporation, Clinton, Mass., a corporation of Massachusetts

Application July 27, 1939, Serial No. 286,762

8 Claims. (Cl. 200—60)

This invention relates broadly to flashlights and electric hand lanterns and more specifically to a circuit closer therefor particularly adapted for so-called pen-lights which are of about the same general size and shape as a fountain pen, or only slightly larger, so that they can be carried in the pocket, although not so limited.

Circuit closers of this general type have been located in the bottom cap of the flashlight and have comprised a spring pressed plunger to cause a completion of the circuit, either by urging that battery terminal which is normally separated from the lamp terminal into contacting or circuit making position therewith or by completing the circuit from the casing to the zinc cup terminal of the battery.

One object of the present invention is to complete the circuit from the casing to a battery terminal by a plunger-type conductive element.

Another object of the invention is a circuit closer of the character described having three positions, to wit, an open circuit position, a "flash" position and a "steady light" position.

A further object of the invention is to provide a yielding circuit closing member in a circuit closer of the character described.

It is also an object of the present invention to retain the battery terminal against the lamp terminal at all times, even when the circuit making plunger is in the open circuit and "flash" positions.

The invention also has for an object a circuit closer of the character described in which allowance is made for variations in the length of the dry cells.

A further object of the invention is switch mechanism which may be removable as a unit from the flashlight to permit the insertion and replacement of dry cells.

The invention also seeks a circuit closer which is practical from the standpoint of ease and cheapness of manufacture and effectiveness and durability in use.

These and other objects of the invention and the means for their attainment will be more apparent from the following detailed description, taken in connection with the accompanying drawing illustrating various embodiments by which the invention may be realized and in which:

Figure 1 is a view showing a flashlight, partly in longitudinal axial section showing the circuit closer of this invention in open circuit position;

Figure 2 is a fragmentary view showing the

circuit closer of this invention in closed circuit position;

Figure 3 is a transverse sectional view, taken in the plane indicated by the line 3—3 of Figure 2 and looking in the direction of the arrows and showing specifically the bottom or end cap of the flashlight with the head of the circuit making plunger removed to show details of construction;

Figure 4 is a transverse sectional view taken in the plane indicated by the line 4—4 of Figure 1 and showing particularly the spacing or positioning devices associated with the circuit closer;

Figure 5 is a view showing a modified form of circuit closer, and

Figures 6 and 7 are views showing the respective component elements of the cruciform battery positioning element of this invention.

For the purpose of illustration, a cylindrical flashlight casing is indicated at 1 having the removable end cap 9 within which is disposed the reflector. This casing 1 carries, in any convenient manner, a lamp supporting member 11 in electrical connection with the casing 1 and formed with or otherwise supporting, a lamp socket 12 adapted to receive the threaded lamp base 14 forming one lamp terminal. The other lamp terminal is indicated at 15 and is adapted, according to the preferred conception, to be always in electrical connection with one terminal, shown as the central terminal 16, of the battery 17 of dry cells.

The opposite or lower end of the casing 1 is formed with or otherwise provided with threads 19 for the reception of the threaded portion 18 of what may be considered the bottom cap 21. The threads 18 of this bottom cap are shown as telescoping within the casing and a peripheral bead 20 limits inward movement and forms an inner annular groove which may be utilized in the modification of Figure 5, in a manner described in connection with that figure.

The circuit closer of this invention is carried by the bottom cap 21. Conveniently, the bottom cap 45 or end wall thereof 22 is apertured, as at 24, and the rim of aperture 24 is conveniently provided with a plurality of spaced inwardly directed fingers or lugs 25, shown in this instance as three in number, although it will be obvious as the description proceeds that the positioning lugs 25 serve primarily as means to retain the plunger in steady light position and that a single lug 25 could, in many instances, serve the purpose.

Disposed in the aperture 24 is a cylindrical member shown conveniently as a tubular metallic

or cup-shaped member 26, the bottom 23 of which is pierced or otherwise formed with an aperture 24 by which is secured, as by a crimping or riveting operation, the shank 30 of a knurled operating knob 31. The end of the cylinder 26 is formed proximate the knob 31 with one or more longitudinally extending slots, recesses or grooves 33 corresponding in position to the lugs 25 and adapted to receive the same whereby relative rotation of the tubular plunger 26 in its open circuit position, and with respect to the end cap 22 is prevented and the wall 28 at the inner end of each slot 33 serves as an abutment limiting the outward movement of the plunger 26.

These slots or grooves 33 extend from the abutments 35 to the end 28 of the plunger thereby permitting the plunger to be inserted in the aperture 24 from above, as viewed in Figure 1, whereafter the knurled head 31 may be secured in position, thereby preventing disassembly of the two parts.

Considering the head 31 and the member 26 as the plunger as a whole, it will be noted that a circumferential groove 36 is formed in the plunger, in this instance, by the reduced shank 30 of the head. It will be apparent that as the plunger 26 is moved inwardly to the position shown in Figure 2, which is the circuit closing position of the switch of this invention, and the head 31 then rotated until the bottom wall 28 is caused to overlie or extend within the bottom 22 of the bottom cap, that the plunger is held inwardly of the bottom cap, in what will herein-after appear as the circuit closing position.

Adapted to reciprocate within the tubular plunger 26, is a cruciform positioning member 37, 38. This cruciform positioning member 37, 38 is preferably composite being conveniently formed of two fiber plates, one indicated at 37 in Figure 6 and one indicated at 38 in Figure 7. Each plate is formed with a wider or base portion 39 and a narrower or upper portion 40 defined by upwardly facing shoulders 41. Member 37 is formed with an axial slot 42 entering from its upper end on the medial line of the member. Member 38 is of the same shape but is formed with a slot 43 extending inwardly from its lower edge. The inner ends 44 of the both slots coincide so that these two members may be dove-tailed together to form the cruciform member shown in Figures 1, 2 and 4. The dot and dash lines 45 in Figure 6 define that portion of the end 39 which would be within the slot 43.

The shoulder 41 receives a coil spring 46 which is seated at its one end against the abutment 35 and has its extremity 47 bent outwardly to engage the annular shoulder or a rib 48 formed in the side wall of the plunger 26. The other end of the coil spring encircles the end portion of the positioning member 37, 38, said end portion in each instance, being indicated generally at 49 and engages the shoulder 41 to urge the positioning member 37, 38 inwardly against the bottom or zinc cup terminal of the battery 17.

To position the plunger concentrically in the bottom cap, a cylindrical shell member 49 may be provided which has an apertured bottom 50. This shell member 49 is first slipped on the plunger 26 over the end 28 and positioned on a rib 52 formed on the plunger before the plunger is entered into the aperture 24.

A second resilient means shown as coil spring 53 encircles the open ended or inner extremity 54 of the plunger 26 and has an end 55 bent inwardly to engage the plunger and retain the spring in

position, the position of the spring being limited by the rib 52.

It will be recognized that in actual commercial practice, the battery 17 will vary in length and the tip 13 of the lamp, that is, the soldered portion 13 will also vary in length. The spring 46 compensates for these variations. When the lamp 14 is screwed into the lamp socket 12, it may drop further into the lamp socket than some other lamp, due to variations in the amount of threads on the lamp base, or due to variations in the depth of the threads or for some other reason. If desired, therefore, the bottom of the lamp socket may be formed with an inturned lip 57.

The method of assembling the circuit closer of this invention will be apparent from the foregoing description. Suffice it to say that the plunger is first passed through the aperture in the shell member 49 and then the plunger and shell member are entered into the bottom or open side of the end cap 21 with the bottom end of the plunger passed through the aperture 24. Thereafter the knob 31 is affixed. The spring 46 may thereafter be inserted within the plunger and the non-conductive positioning member 37, 38 inserted within the spring. Thereafter, the contact spring 53 is applied to the outer surface of the plunger.

A modification of the invention is illustrated in Figure 5 in which the positioning member 37, 38 is provided with ears or lugs 58 whereby the positioning member 37, 38 is retained within the plunger by an inwardly turned rim 60 thereon. If desired, also, a tongue 62, Figure 5, may be formed on the wall 49 of the cup-shaped shell 45-53 which tongue is outwardly pressed and adapted to be received within the groove 64 formed in the bottom cap, as a further means of retaining the parts against displacement.

In operation, and bearing in mind the fact that the terminals 15 and 16 of the lamp and dry cell, respectively, are maintained constantly in contact, by means of the spring pressed positioning means 37, 38 a momentary illumination of the lamp may be effected by pressing inwardly on the head 31 of the plunger. This carries the conductive spring 53 into contact with the zinc cup terminal of the battery 17 and completes the circuit from the conductive casting 7, conductive bottom cap 21, shell 49, plunger 26 to the spring 53. Obviously, even though the shell 49 were omitted the circuit would be completed through the bottom wall 22 of the bottom cap and the plunger 26. If the lamp is to remain illuminated so as to give a steady light from the flashlight, the plunger is pressed inwardly as before to bring the spring 53 into contact with the zinc cup terminal of the dry cell 17 and when the groove 36 is in register with the bottom 22, the knurled end 31 may be turned to bring the wall 28 beneath the wall 21 to retain the plunger in circuit closing position with the yielding contact member 53 in engagement with the zinc cup terminal of the battery.

It will thus be seen that a circuit closer has been proposed which is applicable to any type of flashlight or hand lantern in which the plunger, as a whole, as a contact making member is retained out of contact with the coacting terminal except when pressure is intentionally applied to the thumb piece 31. In the illustrated embodiment the positioning means 37, 38 is shown as insulatory but it will be obvious that insulation at any other point, say, by making the

plunger 26 of insulating material or surfacing the inside of the plunger with a fiber sleeve, will equally serve the purpose. Such a circuit closer is particularly adapted to flashlights of the penlight type since they can be carried in the pocket without danger of closing the circuit except by the intentional act of the operator. Moreover, while a coil spring 53 is illustrated as the contact making member it will be obvious that the use of any kind of resilient conductive means is solely to compensate for variations in battery length and other components of the flashlight and if this is undesired, the contact may be made by the tube 54 or other unyielding plunger-like element.

Various modifications will occur to those skilled in the art in the composition, configuration and disposition of the component elements going to make up the invention as a whole as well as in the selection and/or combination of particular components to accomplish a desired result and no limitation is intended by the phraseology of the foregoing description or illustrations in the accompanying drawing, except as indicated in the appended claims.

What is claimed is:

1. A circuit closer for flashlights in which one battery terminal is electrically connected with one lamp terminal, the combination with an apertured casing portion, of a tubular plunger formed with a peripheral groove and at least one longitudinal groove, said casing portion being formed with a lug for reception in the longitudinal groove, a non-conductive plunger within the tubular plunger, a coil spring engaging the non-conductive plunger to urge the same against the other battery terminal and a coil spring carried by the tubular plunger and adapted when the tubular plunger is in circuit closing position to contact and make electrical connection with the battery terminal.

2. A circuit closer for flashlights in which one battery terminal is electrically connected with one lamp terminal, the combination with an apertured casing portion, of a tubular plunger formed with a peripheral groove and at least one longitudinally extending groove, said casing portion being formed with a lug for reception in the longitudinally extending groove, an apertured shell within the casing portion in which the plunger is guided, a non-conductive plunger within the tubular plunger, a coil spring engaging the non-conductive plunger to urge the same against the other battery terminal and a coil spring carried by the tubular plunger and adapted when the tubular plunger is in circuit closing position to contact and make electrical connection with the battery terminal.

3. A circuit closer for flashlights in which one battery terminal is electrically connected with one lamp terminal, the combination with an apertured casing portion, of a tubular plunger formed with a peripheral groove and a shoulder and at least one longitudinal groove, said casing portion being formed with a lug for reception in the longitudinal groove, a non-conductive plunger within the tubular plunger and formed with a shoulder, a coil spring encircling the non-conductive plunger and disposed between the two shoulders and yielding conductive means carried by the tubular plunger and adapted when the tubular plunger is in circuit closing position to contact and make electrical connection with the other battery terminal.

4. A circuit closer for flashlights in which one

battery terminal is electrically connected with one lamp terminal, the combination with an apertured casing portion, of a conductive tubular plunger formed with a peripheral groove and a first shoulder and a second shoulder and at least one longitudinal recess, said casing portion being formed with a lug for reception in the recess, a non-conductive plunger within the tubular plunger and formed with a shoulder, a coil spring encircling the non-conductive plunger and disposed between the last named shoulder and the first shoulder and a coil spring encircling the conductive plunger and positioned by the second shoulder and adapted when the tubular plunger is in circuit closing position to contact and make electrical connection with the other battery terminal.

5. A circuit closer for flashlights in which one battery terminal is electrically connected with one lamp terminal, the combination with an apertured casing portion, of a conductive tubular plunger formed with a peripheral groove and a first shoulder and a second shoulder and at least one longitudinal groove, said casing portion being formed with a lug for reception in the longitudinal groove, a cruciform composite non-conductive plunger within the tubular plunger and formed with a shoulder, a coil spring encircling the non-conductive plunger and disposed between the last named shoulder and the first shoulder and a coil spring encircling the tubular plunger and positioned by the second shoulder and adapted when the tubular plunger is in circuit closing position to contact and make electrical connection with the battery terminal.

6. A circuit closer for flashlights in which one battery terminal is electrically connected with one lamp terminal, the combination with an apertured casing portion, of a tubular plunger formed with a peripheral groove and a first shoulder and a second shoulder and at least one longitudinally extending groove, said casing portion being formed with a lug for reception in the longitudinally extending groove, a composite non-conductive plunger within the tubular plunger, said composite plunger comprising two plates each formed with a shoulder, said plates dovetailing together and whereof the portion defined by the shoulder is of lesser diameter, a coil spring encircling that portion of the non-conductive plunger which is of lesser diameter and disposed between the last named shoulder and the first shoulder and a coil spring encircling the tubular plunger and positioned by the second shoulder thereon and adapted when the tubular plunger is in circuit closing position to contact and make electrical connection with the battery terminal.

7. A circuit closer for flashlights in which one battery terminal is electrically connected with one lamp terminal, the combination with an apertured casing portion formed with an annular groove inwardly thereof, of a tubular plunger formed with a peripheral groove and at least one longitudinally extending groove, said casing portion being formed with a lug for reception in the longitudinally extending groove, an apertured shell within the casing portion in which the plunger is guided, said shell being formed with a finger for engagement in the annular groove in the casing portion, a non-conductive plunger within the tubular plunger, a coil spring engaging the non-conductive plunger to urge the same against the other battery terminal and a coil spring carried by the tubular plunger and adapted when the tubular plunger is in circuit closing position to

contact and make electrical connection with the battery terminal.

8. A circuit closer for flashlights in which one battery terminal is electrically connected with one lamp terminal, the combination with an apertured casing portion, of a tubular plunger formed with a peripheral groove and at least one longitudinally extending groove, said casing portion being formed with a lug for reception in the longitudinally extending groove, a non-conductive plunger formed with a shoulder within the

tubular plunger, said tubular plunger being formed with an inturned rim to engage the shoulder and retain the non-conductive plunger within the tubular plunger, a coil spring engaging the non-conductive plunger to urge the same against the other battery terminal and a coil spring carried by the tubular plunger and adapted when the tubular plunger is in circuit closing position to contact and make electrical connection with the battery terminal.
